UNITED STATES PATENT OFFICE.

JACOB R. BURKHARDT, OF SPRINGFIELD, OHIO, ASSIGNOR TO THE SPRINGFIELD METALLIC CASKET COMPANY, OF SPRINGFIELD, OHIO, A CORPORATION OF OHIO.

MEANS FOR SECURING CASKETS IN SHIPPING BOXES.

1,426,355.

Specification of Letters Patent Patented Aug. 22, 1922.

Application filed November 21, 1921. Serial No. 516,616.

To all whom it may concern:

Be it known that I, JACOB R. BURKHARDT, a citizen of the United States, residing at Springfield, in the county of Clark and State 5 of Ohio, have invented certain new and useful Improvements in Means for Securing Caskets in Shipping Boxes, of which the following is a specification.

My invention relates to means for securing 10 burial caskets, or structures of a similar nature, in shipping cases.

The object of my invention is to provide 15 a simple and effective fastening device which may be readily applied to a conventional type of burial casket for the purpose of securely holding the same in a shipping case for transportation of such a nature as to obviate the necessity of drilling holes in the bottom of the casket, or otherwise altering 20 the same, and also of such a nature as to present no protruding parts upon the casket bottom, when the casket is removed from the box.

In the accompanying drawings:

25 Fig. 1 is a bottom plan view of a burial casket showing parts of my improved device applied thereto.

Fig. 2 is an enlarged view of a portion of 30 the under side of the casket bottom, showing one of the fastening members.

Fig. 3 is a vertical section of a portion of 35 a shipping case and casket with one of my fastening devices applied thereto.

Fig. 4 is a perspective view of one of the 40 fastening members.

Fig. 5 is a detail section showing a modification.

Referring to the drawing, 1 and 2 represent, respectively, a portion of a side and 45 bottom of a wooden shipping case; 2 representing the bottom of a metallic casket and 3 a portion of one of the sides. In forming the bottom there is pressed therein a recess 4 near the marginal edges thereof, which in 50 the present case is shown as a continuous groove, but which may be formed as a series of recesses. The walls of the groove or recess are preferably of concave form, as shown.

Secured in the groove 4 near each corner 55 of the casket bottom, preferably by spot welding, is a metallic plate, the respective ends of which are concavo-convex shape as indicated at 5, to conform to the contour of the bottom of the groove, and the central portion of which is offset as indicated at 6 so

as to stand away from the bottom of the groove as shown in Fig. 3. The central portion 6 is formed with a threaded opening 7, the metal of the plate being so punched and pressed as to provide a central boss 6^a 60 through which the opening extends. These plates are installed as permanent attachments and when the casket or other structure is placed in the shipping box for transportation, bolts 8 are inserted through openings 65 in the bottom of the box and threaded in the openings 7 to draw and hold the casket bottom tightly against the bottom of the box.

In Fig. 5 there is shown a modification in which, instead of threading the opening 7, a 70 nut 9 is placed between the offset portion 6 of the plate and the bottom of the casket, into which nut the bolt is threaded.

Having thus described my invention, I 75 claim:

1. In a structure of the character described, the combination, with a shipping box, of a structure capable of being received therein and having a bottom formed with a recess, a plate secured in said recess, said 80 plate having a threaded opening to receive a bolt extended through the bottom of said box.

2. A structure having a bottom formed with a recess, and a plate secured in said recess having a threaded opening to receive a 85 bolt for the purpose of securing said structure in a shipping box.

3. A structure having a bottom formed with a concave recess, and a plate having 90 convex faces fitted to the walls of said recess and also having a central offset portion having a threaded opening to receive a clamping member.

4. The combination, with a shipping box, 95 of a structure having a bottom formed with recessed portions, a plurality of plates fitted in said recesses, each plate having a threaded opening, and bolts extending through the box bottom and into said threaded openings 100 to secure said structure in said box.

5. The combination, with a shipping box, 105 of a structure having a metallic bottom formed with concave recessed portions, of a plurality of plates having convex faces fitted in said recessed portions, each plate having a threaded opening and bolts extending through the box bottom and threaded in said openings to clamp the structure to the box bottom.

6. A structure having a bottom formed with a recess, a plate secured in said recess and having an offset part with an opening, a clamping member passing through an enclosing casing and also through said opening, and means for securing said member in clamping position.

7. The combination, with a shipping box, of a structure having a bottom formed with a recess, a bolt passing through the bottom of the box and into said recess, and threaded devices carried in said recess to receive and secure said bolt.

8. The combination, with a shipping box, of a structure having a bottom formed with a recess, and a plurality of devices located at different points about the bottom of said structure for securing said structure in said box, each of said devices comprising a pair of members, one of which is secured in said recess and the other of which projects through said box together with means for detachably securing said members together.

In testimony whereof, I have hereunto set my hand this 10th day of November 1921.

JACOB R. BURKHARDT.
